CLAIM

The ornamental design for cushioning shoe inserts, as shown and described.

DESCRIPTION

FIG. 1 is a rear perspective view of a first embodiment of cushioning shoe inserts, showing my new design;

FIG. 2 is a front perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a right side elevation view thereof;

FIG. 8 is a left side elevation view thereof;

FIG. 9 is a rear perspective view of a second embodiment of cushioning shoe inserts, showing my new design, with sewn stitching between top and bottom portions;

FIG. 10 is a front perspective view thereof;

FIG. 11 is a top plan view thereof;

FIG. 12 is a bottom plan view thereof;

FIG. 13 is a front elevation view thereof;

FIG. 14 is a back elevation view thereof;

FIG. 15 is a right side elevation view thereof; and,

FIG. 16 is a left side elevation view thereof.

The dot-dashed broken lines shown in the drawings represent a boundary of the cushioning shoe inserts that forms no part of the claimed design.

1 Claim, 6 Drawing Sheets
